(57) **CLAIM**

The ornamental design for a sanitary article, as shown and described.

DESCRIPTION

FIG. 1 is top plan view of a sanitary article showing my new design.

FIG. 2 is a bottom plan view thereof.

FIG. 3 is a rear elevational view thereof.

FIG. 4 is a front elevational view thereof.

FIG. 5 is a right side elevational view thereof; and,

FIG. 6 is a left side elevational view thereof.

The broken lines illustrate portions of the sanitary article and form no part of the claimed design.
